UNITED STATES PATENT OFFICE.

IRA O. WRIGHT, OF BALTIMORE, MARYLAND, ASSIGNOR, BY MESNE ASSIGNMENTS,
TO THE SYMINGTON COMPANY, A CORPORATION OF MARYLAND.

DRAFT RIGGING.

Application filed March 30, 1922. Serial No. 548,065.

The invention relates to draft rigging for railway cars, and more particularly to that class of draft rigging designed for the underframes of freight cars, my present invention constituting a continuation in part of my copending application filed April 29, 1920, and bearing Serial Number 377,477, now patent No. 1,457,278, dated May 29, 1923.

10 The principal object of my invention is to provide in combination a backstop and center sill tie casting, and a draft rigging in which the coupler is movable rearwardly independently of the yoke in buffing and 15 the buffing loads are transmitted to and carried by said backstop and tie casting.

To this end the main features of the invention comprise a stop member so constructed and arranged as to suitably brace 20 the cushioning mechanism and connected parts and to transmit excessive loads to the car underframe without detriment to the latter, said stop member including a unitary structure forming a center sill tie casting, and provided with rear stop lugs 25 for the cushioning mechanism, and a reinforced buffing face for the yoke.

Another feature of my invention is to provide a combined backstop and tie casting of maximum strength value for the 30 amount of material used, the reinforcing flanges or webs being advantageously disposed to effectively resist the forces to which the stop lugs and buffing face are subjected.

Various other features and objects of the invention are hereinafter brought out in the more detailed description of the particular forms of my invention which have been 40 chosen for purposes of illustration.

In the drawings, wherein I have shown a preferred embodiment of the invention together with modifications thereof,

Figure 1 is a view partly in plan and 45 partly in horizontal section of the center or draft sills of a freight car showing the combined backstop and tie casting connected to said sills and positioned in associated relation with the yoke, coupler and cushioning mechanism.

Figure 2 is a longitudinal vertical sectional view of the parts shown in Figure 1.

Figure 3 is a view partly in plan and partly in horizontal section of the back-

stop member, the section being taken on 55 the line 3-3 of Figure 4.

Figure 4 is a vertical longitudinal sectional view of the backstop casting on the line 4-4 of Figure 3.

Figure 5 is a transverse sectional view on 60 the line 5-5 of Figure 4 looking in the direction of the arrows, a portion of the backstop member being shown in end elevation.

Figure 6 is a fragmentary top plan view 65 of the center or draft sills and yoke showing a modified form of combined backstop and tie casting, omitting the rear stop lugs.

Figure 7 is a vertical longitudinal sectional view of the modified structure shown 70 in Figure 6.

Figure 8 is a vertical transverse sectional view through the center sills, the back stop casting being shown in end elevation.

Figure 9 is a fragmentary top plan view 75 of the center or draft sills, showing still another modified form of backstop member, the yoke being shown in section and the rear follower of the cushioning mechanism engaging the rear stop lugs provided 80 on the rear stop member.

Figure 10 is a vertical longitudinal sectional view of the modified structure shown in Figure 9.

Figure 11 is a vertical transverse sectional view through the center sills on the line 11-11 of Figure 9 viewed in the direction of the arrows.

Referring to the drawings in which similar reference characters designate corresponding parts in the several views, the center or draft sills 1-1 are shown as of built-up channel construction, the forward draft end of said sills being formed of Z-bars riveted to the angle bars and vertical plate constituting the channel center sills, as clearly shown in Figure 5. The end sill 2 has connected therewith the striking casting 3 and a coupler carry iron, is shown at 4. All of the said parts may 90 be of suitable or desirable construction.

The Z-bars of the draft sills 1-1 are each provided at their forward ends with a longitudinally extending slot 5 and to the inner face of each bar or sill is riveted a 95 cheek plate or frontstop casting 6 formed with a slot 7 adapted to register with the said slots 5 in the sills 1. The cheek plates

- 6 on their inner faces are each provided with inwardly extending flanges 8 which are cut away, as at 9, to provide clearance space for the side faces of the yoke. The 5 flanges 8 also reinforce the forward stop lugs 10 which latter are operatively associated with the forward follower of the cushioning mechanism, as shown in Figures 1 and 2.
- 10 The yoke or coupler connecting means includes the vertical yoke 11 which is provided at its forward end with the headed hood 12, the vertical side walls of which are provided with longitudinally extending key receiving 15 slots 13. The forward portions of these slots are preferably furnished with reinforcing members 14 to increase the bearing at these points for the coupler key 15, and it is to clear these enlargements that the flanges 8 20 are cut away at the points 9, as hereinbefore described. The key 15 is adapted to slidably connect the coupler 16 to the yoke 11, the said key when in normal position of the gear, engaging the rear wall of the slot in 25 the coupler, and engaging at its forward edges against the forward ends of the slots 13 in the yoke head, the said key being also adapted to extend through the slots 7 in the cheek plates and normally position at an 30 intermediate point in the slots. It will be noted that the rear ends of the slots 13 and the rear ends of the slots 7 substantially coincide. This construction permits an inward movement of the coupler independently 35 of the yoke under buffing stresses.
- The combined backstop and tie casting 17 is arranged between and firmly connected to the center sills so as to deliver all of the buffing stresses thereto, said casting also 40 forming the center filler between the outwardly extending portions of the bolster. This backstop member is positioned at a suitable distance in the rear of the forward stop castings so as to provide sufficient space 45 for the interpositioning of the cushioning mechanism indicated by the diagonal dot and dash lines, and including the front and rear followers, as shown in Figures 1 and 2.
- Forwardly extending follower engaging 50 lugs 18 are provided on the stop member, said lugs forming continuations of the side walls 19 of the casting and constituting rear stop lugs for the rear follower of the cushioning mechanism. The lugs 18 are braced 55 by the webs or flanges 20 which project inwardly and have edges arranged parallel with the side walls 19 for a distance in the rear of said lugs, the topmost of the flanges 20 flaring outwardly at their rear ends, as indicated at 21, and merging into the side walls, as shown. The lowermost flanges 20 extend inwardly of the casting and parallel with the side walls 19, as shown in dotted lines in Figure 3, said flanges being slightly upwardly offset and terminating 60 in the floor of the casting to be presently described. The intermediate central flanges 20 terminate in a vertical transverse web or wall 22, said wall integrally uniting the side walls 19 and being located at a point 70 in the rear of the vertical stop lugs 18 in normal spaced position from the yoke 11, as shown. Arranged between the flanges 20 and bracing the stop lugs 18 are relatively short triangular webs 23.
- A buffing face 24 is provided on the web or upright flange 22 and is adapted to receive the buffing stresses through the yoke 11 when the latter moves thereagainst. The web 22 is relatively deep, the forward portion of the side walls 19 and lowermost flanges 20 being offset in a lower plane to permit of the maximum buffing face for the yoke and full bearing faces on the stop lugs 18 with which the rear follower engages. 75 A horizontally disposed buffing web 25 transversely connects the opposite side walls of the casting, said web being intermediately disposed between the top and bottom edges of the vertical flange or wall 22 and connecting said wall with the center thimble. Additional vertically arranged webs 26 reinforce the vertical wall 22 and extend longitudinally of the casting, said vertical webs being centrally located, and connecting the 80 top and bottom webs 27 and 28. 85
- The top and bottom webs are preferably extended laterally and joined to the side walls 19 so as to form respectively, the upper and lower horizontal walls of the casting. Likewise the transversely extending buffing web 25 extends laterally and joins the respective side walls intermediate the top and bottom webs. The bottom wall or floor web of the casting terminates at a point 90 well back of the vertical flange 22, thereby providing for the entry of the connecting rivets and at the same time providing a casting 95 which is easy to manufacture. 100
- The side walls are slightly offset, as shown 110 in Figure 3 and are further united by means of a transverse web 29, the inner portion of which is interrupted by the center thimble 30, as will be seen by reference to Figures 3 and 4. The vertically disposed webs 26 115 terminate in the side walls of the thimble, portions thereof extending rearwardly of the casting, as shown. The back-stop casting is connected to the built-up center sills by means of rivets 31, said rivets also serving 120 to unite the sections constituting the sills. The offset portions of the casting permit the several sections of the center sills to be longitudinally positioned in the continuous manner shown. 125
- In the normal position of the parts illustrated in Figure 1, it will be seen that the rear follower engages the forward faces of the stop lugs 18, and the front follower engages the rear faces of the front stop lugs 130

10. Under buffing movement the coupler is moved rearwardly, and transmits the load to the cushioning mechanism which is in turn supported by the rear follower and 5 the stop lugs 18. On forward movement the yoke and coupler move together and the load is transmitted from the yoke to the cushioning mechanism and from the latter to the front stops connected to the car sills. 10 It frequently happens that the load to which the draft rigging is subjected exceeds the capacity of the cushioning mechanism, and my present construction is particularly designed to afford efficient means for 15 absorbing, without detriment to the car, this excessive overload. Should the buffing load exceed the capacity of the cushioning mechanism, the rear end of the yoke will engage the buffing face 24, and the load will be carried at three points, namely the rear stop lugs 18 and the vertical flange 22.

Figures 6, 7 and 8 show a slight modification of the rear stop member and in these Figures the rear end of the yoke 32 is provided with a plurality of spaced walls 33 which are connected by a plurality of vertically extending webs 34 and the transversely extending web 35, the said structure forming a strong load transmitting member 20 which is adapted to normally contact with the abutting face 36 provided on the web 37 of the back stop and tie casting 38. The web 37 in this form of stop member is reinforced by a plurality of vertically 25 extending webs 39 uniting the top and bottom portions 40 of the casting. In addition, a centrally located and horizontally disposed transverse buffing web 41 connects the side walls 42 of the casting and the vertical web 37 with the center thimble. In 30 this form of my device the entire buffing load is transmitted directly to the central portion of the backstop, and rear stop lugs, such as those indicated at 18 and hereinbefore 35 described, are not employed.

In the modified form of backstop member shown in Figures 9, 10 and 11, the rear end of the yoke 43 is solid, the said end forming a strong load transmitting member 40 which is adapted normally to be spaced from the buffing face 44 of the web 45. The rear follower 46 of the cushioning mechanism is designed to engage rear stop lugs 47 formed integrally with and projecting from the backstop casting 48. The vertical web 45 in the casting 48 is braced similarly to that shown in Figure 6, but in addition, the top and bottom webs 49 of the casting extend forwardly and terminate in the stop lugs 47. These stop lugs are braced by intermediate webs 50 extending between the forward portion of the stop lugs and the transversely extending web 45.

55 The top and bottom webs 49 are preferably extended laterally and joined to the side

walls 51 of the casting 48 so as to form respectively, the upper and lower horizontal walls therefor. Likewise the transversely extending buffing web 52 is continued in effect forwardly of the vertical flange 45 by the 70 laterally extending reinforcing flanges 50 which, as shown, merge into the stop faces 47, as hereinbefore described. It will be evident that these stop lugs 47 are braced at the top and bottom respectively by the 75 extensions of the upper and lower walls 49 of the casting, and at the center by the extensions from the vertical web or flange 45. Intermediate the web 52 and the upper and lower braces I also preferably provide 80 additional braces 53 for the stop lugs 47. These additional braces extend from the marginal edges of the web 45, as will be clear from an inspection of Figure 10 of the drawings. By terminating the bottom 85 wall or floor web of the casting at a point adjacent the flange or web 45, I provide for the entry of the connecting rivets between the wall and the web 52, and at the same time provide a casting which is easy to manufacture since the opening between the said wall and the web 52 permits the ready removal of the cores used in the production of the casting. In this modified form of my 90 invention the buffing load is imparted through the rear follower 46 to the stop lugs 47, and in the case of excessive loads, the yoke 43 is caused to move against the buffing face 44 of the web 45.

In the several forms of my device it will be understood that the yoke is supported at an intermediate point by a carry iron 54 which may be connected to the lower outstanding flanges of the Z-bars in any suitable manner. For convenience, the carry 95 iron 54 is shown connected by means of a plurality of bolts 55.

I claim:—

1. In a draft rigging, the combination 110 with spaced center sills, of a yoke slidably mounted therebetween, a casting interposed between said sills in the rear of said yoke and having follower engaging lugs, means on said casting for engaging said yoke after a predetermined movement of the same, said yoke being normally spaced from said means and being adapted to contact the same upon a rearward movement thereof, means for reinforcing said first named 115 means including a plurality of vertically disposed webs arranged in alignment with the yoke and spaced inwardly of the follower lugs, and means for connecting said casting to said center sills.

2. In a draft rigging, the combination 120 with the center sills, of a combined stop and tie casting located between said sills, said casting having adjacent one end of each side wall an inwardly extending flange, said 125 flanges being adapted to form follower stop

lugs, a floor forming web connected to said side walls, extensions from said web for bracing the lower portions of said lugs, and a buffing web located above said floor forming web and extensions on said last named web for bracing said lugs at an intermediate point.

3. In a draft rigging, the combination with spaced center sills, of a stop member located between and connected to said sills, said member comprising side walls adapted to form follower engaging lugs, means for connecting the side walls to the center sills, a vertical web uniting said walls and having a buffing face, a buffing web formed integrally with said side walls and adapted to reinforce said vertical web, between the upper and lower edges thereof, said web being continued forwardly to provide reinforcing means for the follower engaging lugs.

4. In a draft rigging, the combination with spaced center sills, of a stop member located between and connected to said sills, said member comprising side walls formed with follower engaging lugs, and means including a plurality of vertical webs arranged longitudinally and centrally of the stop member between the lugs and a plurality of horizontal webs arranged transversely of the member for uniting said side walls.

5. In a draft rigging, the combination with spaced center sills of a stop member located between and connected to said sills, said member comprising side walls adapted to form follower engaging lugs, and means including relatively long vertical webs and an intermediate shorter horizontal web uniting said side walls.

6. In a draft rigging, the combination with spaced center sills, of a stop member located between and connected to said sills, said member comprising side walls adapted to form follower engaging lugs, and means including relatively long vertical webs centrally located of the member and a transverse vertical web at the forward ends thereof, said last named vertical web being located in the rear of said follower engaging lugs.

7. In a draft rigging, the combination with spaced car sills having draft sills connected thereto, of a combined back stop, tie and center casting located between and connected to said sills, said casting being formed of oppositely disposed side walls each of which is offset at its forward end for receiving an adjacent draft sill, follower engaging lugs provided on each offset portion, and a web uniting said walls and provided with a buffing face in the rear of said lugs.

8. In a draft rigging, the combination with spaced car sills having draft sills con-

nected thereto, of a combined back stop, tie and center casting located between and connected to said sills, said casting comprising side walls each of which is laterally offset for receiving the inner end of the draft sill between the outer face of the wall and an adjacent car sill, follower engaging lugs provided on said offset portions, and a web uniting the offset portions of the side walls and providing a buffing face at the rear of said lugs.

9. In a draft rigging, the combination with spaced center sills and draft sills, of a combined backstop, tie and center casting located between and connected to said sills, said casting comprising side walls each having its forward portion inwardly offset to accommodate the draft sills and adapted to form at its extreme forward end a follower engaging lug, and a web uniting said walls and provided with a buffing face in the rear of said lugs.

10. In a draft rigging, the combination with spaced center sills, of a stop member located between and connected to said sills, said member comprising oppositely disposed side walls each of which is vertically offset at its forward end, stop lugs provided on said offset portions, and a transversely disposed vertical web uniting said offset portions of the side walls and adapted to form a relatively large buffing face, said web terminating short of the bottom edges of said offset portions.

11. In a draft rigging, the combination with spaced car sills having draft sills connected thereto, of a stop member located between or connected to said sills, said member comprising oppositely disposed side walls each of which is vertically and laterally offset at its forward end for receiving the inner end of an adjacent draft sill, stop lugs provided on said offset portions, said lugs being of a depth and width corresponding to said offset, and a transversely disposed web uniting said offset portions of the side walls and arranged to form a buffing face.

12. A stop casting for railway draft rigging involving spaced side walls, each having its forward end inwardly and downwardly offset, top and bottom walls uniting said side walls, and a longitudinally extending vertical wall connected to the respective top and bottom walls, and a transversely extending vertically disposed wall connected to said vertical wall and side walls near their forward ends, said transverse wall forming a buffing web, and stop lugs provided at the forward ends of said side walls in spaced relation to said buffing web.

13. A stop casting for railway draft rigging comprising spaced side walls, top and bottom walls uniting said side walls, a ver-

- tical wall connected to said top and bottom walls, a transverse wall connected to the side walls and adapted to engage a movable element of the draft rigging, and means for reinforcing said last named wall, said means including vertically disposed webs connecting said vertical wall with the top and bottom walls of the casting, and a horizontally disposed web extending rearwardly from said vertical wall and uniting the said side walls. 10
14. A stop casting for railway draft rigging comprising spaced side walls, top and bottom walls uniting said side walls, a vertical wall adapted to engage a movable element of the draft rigging, and means for reinforcing said last named wall, said means including a plurality of longitudinally and centrally arranged vertical webs connecting said vertical wall to the top and bottom walls of the casting. 15
15. A stop casting for railway draft rigging comprising spaced side walls, top and bottom walls uniting said side walls, a vertical wall adapted to engage a movable element of the draft rigging, and means for reinforcing said last named wall, said means including a plurality of longitudinally arranged vertical webs connecting said vertical wall with the top and bottom walls of the casting, and a horizontal transversely arranged web uniting said vertical wall with the side walls, and said longitudinally arranged vertical walls with each other. 20
- 20 16. A stop casting for railway draft rigging comprising spaced side walls, each of said walls having an inwardly extending portion providing a stop member, top and bottom walls uniting said side walls, a vertical wall uniting said top and bottom walls, and an intermediate horizontal web uniting the side walls and the vertical wall, and means including a plurality of ribs for reinforcing the inwardly extending portions of said side walls. 25
17. A stop casting for railway draft rigging having a center thimble, spaced side walls, top and bottom walls uniting said side walls, a vertical wall uniting said top and bottom walls, and an intermediate horizontal web uniting the side walls and the vertical wall and longitudinally disposed reinforcing ribs arranged above and below said horizontal web adjacent each side wall forwardly of the center thimble. 30
18. A combined stop casting and body bolster center brace having vertically arranged walls transversely disposed to provide spaced rear stop members, side walls adjacent each vertical transverse wall, top and bottom walls uniting said side walls, a longitudinally arranged vertical wall uniting said top and bottom walls, a horizontal web uniting the side walls and the longitudinally arranged vertical wall, and a reinforcing rib uniting the transversely disposed vertical walls and their adjacent side walls. 35

In testimony whereof I affix my signature.
IRA O. WRIGHT.
